James G. Abbott of Philadelphia, Penn.

Assignee

Abbott & Noble of Philadelphia aforesaid,

Letters Patent No. 2244, Dated January 30 1866

Acted dated December 24 1866

Design for the Plate of a Stove.

The schedule referred to in these Letters Patent and making part of the same.

To all whom it may concern:

Be it known that I, James G. Abbott of Philadelphia County of Philadelphia, State of Pennsylvania, have invented or produced a new and original design for plates of a nine plate stove, and I do hereby declare the accompanying Drawing with the following explanation of the same, to form a full, clear and exact description of the said Design.

In the accompanying drawing

Fig. 1, represents the bottom plate of a "Nine Plate Stove" and

Fig. 2, the top plate.

At the edge of the bottom plate 1, is a plain moulding a, and in the centre of the plate is a long depression, of the shape represented in the drawing.

The edge of the top plate 2, is rounded as shown in the drawing, and in the plate are two openings 3, 4, the latter being surrounded by a flange 5.

Patent. The design for plates of a nine plate stove, substantially as shown in and by the accompanying drawing.

In testimony whereof I have signed my name to this specification, in the presence of two subscribing witnesses
